UNITED STATES PATENT OFFICE.

CHARLES D. BROUETTE, OF TOPEKA, KANSAS.

SPRING BOTTOM.

Application filed October 3, 1923. Serial No. 666,835.

To all whom it may concern:

Be it known that I, CHARLES D. BROUETTE, a citizen of the United States, residing at Topeka, in the county of Shawnee 5 and State of Kansas, have invented certain new and useful Improvements in Spring Bottoms; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

This invention relates to spring bottoms in which coil springs are employed to provide the necessary cushion. The primary object of the invention is to provide novel 15 braces or tying-in wires which will maintain the springs in proper spaced relation in such a manner as to prevent sagging. The tying-in wires provide flexible connections between the springs while at the same time permitting sufficient resiliency to permit the 20 springs to resume their original position when the load on the spring is removed. It is an important feature of my invention, that by its construction the necessity for having outside frames is eliminated, and it 25 is also an important feature of the invention that a level upper surface of the spring bottom is insured. The tying-in wires not only brace the spring but they maintain them in proper spaced relation and in the 30 embodiment of the invention selected for illustrative purposes the tying-in wires are provided with broad bearings for engaging the spring coils so that a certain amount of 35 rigidity is provided for the assembled structure. The tying-in wires are so constructed that a simple method of assembly is provided and liability of accidental displacement is eliminated.

In the manufacture of spring bottoms the 40 cost of production is an important feature because competition is keen and in order to be commercially successful a spring bottom must be manufactured inexpensively and yet be capable of extended use without 45 breaking down. All of these features have been taken into consideration in the development of my invention and in practice I have found that parts of the spring bottom can be readily assembled in an expeditious manner so that the ultimate cost of the

spring bottom will be reduced to a minimum. The novel details of construction of the invention will be thoroughly understood and appreciated by reference to the following description in connection with the accompanying drawings, in which—

Fig. 1 is a fragmentary perspective view of a spring bottom constructed in accordance with my invention.

Fig. 2 is an enlarged perspective view of one of the tying-in wires.

Fig. 3 is an enlarged detailed view of the inter-lock between two complementary wires and two complementary spring coils.

Fig. 4 is a detailed perspective view of one 70 end of one of the tying-in wires showing the manner of attaching it to one of the coil springs, and

Fig. 5 is a view showing the hook end 75 of one of the tying-in wires in position to inter-lock with the loop of a complementary wire and at top convolute of one of the coil springs.

Referring now to the drawings by numerals of reference:

1 designates the top frame and 2 the bottom frame of a spring bottom. The bottom frame is shown as provided with longitudinal stay wires 3 and transverse complementary stay wires 4, at the intersections of which are seated the coil springs 5. The outer coil springs are fastened to the frame 1 by wire wrappings 6 and the intermediate rows of springs are fastened one to the other and to the outer coil springs by tying-in 90 wires one of which is illustrated in Fig. 2.

The tying-in wire illustrated in Fig. 2 consists of a strand 7 bent near one end to form an offset portion 8 which constitutes a spring seat in that it rests upon the upper edge of the top convolute of the spring to which it is secured. One end of the strand 7 is bent back upon itself to form a hook 9 and intermediate the hook and the spring seat is a bent off-set open loop 10 to be engaged by a hook on a complementary tying-in wire. At the end of the strand 7 distant from the hook 9 is a coil 11 terminating in a right angular projecting transverse arm 12 bent downwardly to form a notch or loop 13 receiving seat 13 and terminating in a transverse spring engaging hook 14 which is adapted to engage a loop 10 on a complementary tying-in wire and to engage over the top convolute of one of the springs. 110

The complementary tying-in wires are alternately right and left, that is the hooked portion of one wire for connecting two complementary springs is disposed in one direction, whereas the complementary tying-in wire is disposed in an opposite direction and two complementary tying-in wires are off-set one with respect to the other and for the purpose of description it will be assumed that the left of the spring is across the sheet of drawings, that is the left of the spring bottom will be assumed from left to right. The end tying-in wires are somewhat shorter than the intermediate ones, one being indicated at 15, Figure 1 with a hooked portion 16 engaging the frame 1. The strand 15 is fastened to the top convolute of one of the end springs and it is provided with an intermediate loop 10 extending under the top convolute of the spring which it engages, its outer end being fastened by a hook 9 to the spring. In applying the next tying-in wire such as is shown in Fig. 2 the coil portion 11 is caused to engage the top convolute of one of the springs 5 in the manner shown in Fig. 4. The strand 7 is then turned in the direction indicated by the arrow 17 and at the same time the strand is tilted in the direction of the arrow 18 so as to wind the coil 11 about the top convolute of the spring 5 as shown in Fig. 5. The spring containing the tying-in wire 15 is then tilted as is also the spring carrying the tying-in wire 7 so that the hooked portion 14 can engage through the loop 10 and over the top convolute of the spring as shown in Fig. 5 so that an interlock is made as shown in Fig. 3. The opposite end of the strand 7 now engages the left aligning spring of the longitudinal row in which the strand is fastened and the loop 10 is slipped under the top convolute of the second spring in the longitudinal row with the spring seat 8 resting on top of the spring and the hook 9 fastened to the spring by slightly closing the hook to form a secure loop. Now two transverse springs and two longitudinal springs (three in all) are fastened together. Now the operator takes a left hand tying-in member and winds it about the top convolute of the second spring in the second longitudinal row securing it according to the same illustration in Figs. 4 and 5, causing the hook 14 to engage under the loop 10 and over the top convolute of the second spring in the first longitudinal row to form an interlock. The opposite end of the strand just applied being fastened to the third spring in the first longitudinal row in the same manner as described in the first strand 7 and these interlocking arrangements being continued throughout the rest of the spring so when two longitudinal rows of springs are secured together the same process is repeated with respect to the

second and third rows and so on until all of the springs are tied in so that there can be practically no sidewise movement of the spring yet the spring bottom will possess a marked vertical resiliency permitting free play of the springs up and down without liability of their sagging or becoming accidentally misplaced. The tying-in members will maintain the springs in such positions that the top of the spring bottom will be at all times practically horizontal or level, the completed spring bottom affording an efficient yielding support for the mattress. Of course when the springs of the spring bottom are depressed there will be a slight pivotable or sliding contact between the end of the loop 10 and the loop receiving notch 13 so as to provide the necessary flexibility. The coil portions 11 will have a very slight play between the springs in each longitudinal row but while this slight play is permitted both longitudinally and transversely the effective rigidity of the structure will not be sacrificed.

What I claim and desire to secure by Letters-Patent is:

1. In a spring bottom, a plurality of coiled springs, means for securing the bottom portions of the springs in spaced relation to maintain the springs in rows, and tying-in members, each tying-in member comprising a strand bent to provide a spring seat, a loop and a hook at one end, the other end of each strand being coiled to engage the top convolute of a spring, the coil terminating in a right angular arm having a loop receiving seat and a transverse hooked end, the transverse hooked end of each member passing through the loop of a complementary member and interlocking with the top convolute of a spring, the loop of each member being receivable in the seat of the complementary member, the spring seat and first named hook of each member engaging one of the coil springs.
2. In a spring bottom, a plurality of coiled springs, means for securing the bottom portions of the springs in spaced relation, and tying-in members for the upper portions of the spring, each tying-in member comprising a strand having a right angular projecting hooked end and a longitudinally disposed hooked end, the right angular projecting hooked end being joined to the major portion of the strand by a spring engaging coil, the portion of the strand adjacent to the longitudinally hooked end having a transverse open loop to engage under a spring, the right angular projecting hooked end being adapted to engage a spring and interlock with the open loop of a second of said tying in members, the longitudinally hooked end being engageable with the spring.
3. In a spring bottom, a plurality of coiled

- springs, means for securing the bottom portions of the springs in spaced relation and tying-in members for the upper portion of the spring, each tying-in member comprising a strand provided at one end with a spring engaging hook and right angular projecting open loop extending under the upper convolute of one of the springs, the other end of each strand engaging a second spring and having a right angular projecting portion provided with a hooked end extending upwardly through the loop of a complementary member and over the upper convolute of a third spring.
4. In a spring bottom, a plurality of coiled springs, means for securing the bottom portions of the springs in spaced relation, and tying-in members for the upper portions of the springs, each tying-in member comprising a strand bent to provide a spring seat, a spring engaging hook adjacent to the seat and a transverse loop between the seat and the hook, the seat and the hook over-lying the upper convolute of a spring, the other end of the strand engaging another spring and having a right angular projection which passes up under the loop of one tying-in member and over the upper convolute of an additional spring.
5. In a spring bottom, a plurality of coiled springs, means for securing the bottom portions of the springs in spaced relation, and tying-in members for the upper portions of the springs, each tying-in member comprising a strand bent to provide a spring seat, a spring engaging hook adjacent to the seat and a transverse loop between the seat and the hook, the seat and the hook over-lying the upper convolute of the spring, the other end of the strand engaging another spring and having right angular projections which pass up under the loop of one tying-in member and over the upper convolute of an additional spring, the loop of each member lying in a seat in a right angular projection of a complementary member.
6. A locking member for spring bottoms comprising a strand having bent portions to provide a spring engaging seat, one end being hook shaped, the strand having an open transverse loop between the hook and the spring seat, the opposite end of the strand being coiled, the coil terminating in a right angular projection having a bend to form a notch, the extremity of the bend terminating in a hook.

In testimony whereof I affix my signature
CHARLES D. BROUYETTE.
